UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER.

Application filed September 10, 1921. Serial No. 499,638.

To all whom it may concern:

Be it known that I, GEORGE P. WIGGINTON, a citizen of the United States, residing at the city and county of Kalamazoo, State of Michigan, have invented certain new and useful Improvements in Temporary Binders, of which the following is a specification.

This invention relates to improvements in temporary binders.

10 The main objects of this invention are:

To provide an improved temporary binder for the holding of loose sheets, circulars and the like which may be easily adjusted to bind or secure the sheets or to permit their 15 removal and insertion.

A further object is to provide an improved temporary binder which is simple and economical in structure and neat and attractive in appearance.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated in the accompanying drawing, forming a 30 part of this application, in which:

Fig. I is a rear perspective view of my improved binder.

Fig. II is a detail section on a line corresponding to line 2—2 of Figs. I and IV, the 35 post being shown in full lines.

Fig. III is a perspective view of one of the posts.

Fig. IV is a detail section on a line corresponding to line 4—4 of Fig. I.

40 Fig. V is a detail section corresponding to Fig. II of a modified form of my invention, the modification being in the omission of the back of the binder and the arrangement of the binding bars on the covers.

45 In the drawing similar reference characters refer to similar parts throughout the several views and the sectional views are taken looking in the direction of the little arrows at the ends of the section lines.

50 Referring to the drawing, the covers 1, 1 in the embodiment shown in Figs. I and II are connected by a flexible back 3. Within the covers are binding bars 4 hinged to the covers by means of the flexible hinges 5.

55 The binding bars have opposed holes 6

adapted to receive the studs 7 of the binding posts 8. These binding posts are provided with heads 9 engaging the sheet body at the inner side of the binding bars. The posts are arranged in coacting pairs upon opposite sides of the sheet body and in telescoping relation therein, as shown in Figs. II and V. The posts are preferably of semi-cylindrical or D-complementary cross section, their flat faces meeting when the posts are 60 telescoped within the sheet body. The ends of the posts are outwardly beveled at 10 so that their flat faces are guided together, that is, these beveled ends tend to turn the posts bringing their flat faces together. 70

In the modification shown in Fig. V the binding bars 11 are secured to the cover by the flexible hinges 12, the flexible back being omitted; otherwise the structure is the same as described.

75 The binding bars are adjustably connected by means of the coupling members 12 consisting of the section 13 hinged to one of the bars 4 at 14 and the section 15 threaded into the section 12 and having a head 16 detachably engageable with the slot 17 of the other bar.

With this arrangement, the coupling members may be adjusted to accommodate the sheet body, the posts telescoping therein as 85 the sheet body is varied.

My improved binder is very attractive in appearance and is very easily manipulated for the insertion or removal of sheets and when the coupling members are engaged the 90 sheets are very securely bound.

Having thus described my invention, what I claim as new and desire to secure by Letters Patent is:—

1. In a temporary binder, the combination 95 with sheets provided with holes adapted to receive posts, of covers, binding bars hinged thereto, posts provided with collar-like sheet-engaging heads and with studs detachably engaging said binding bars, said posts being arranged in coacting pairs from opposite sides of the sheet body in overlapping relation therein and being of semi-cylindrical complementary cross section, their ends being outwardly beveled, and extensible coupling members for said binding bars disposed at the ends thereof. 100

2. In a temporary binder, the combination with sheets provided with holes adapted to receive posts, of covers, binding bars 105

hinged thereto, posts provided with sheet-engaging heads detachably engaging said binding bars, said posts being arranged in coacting pairs from opposite sides of the sheet body in overlapping relation therein and being of complementary cross section, and extensible coupling members for said binding bars disposed at the ends thereof.

3. In a temporary binder, the combination of covers, binding bars operatively associated therewith, sheet-engaging posts provided with sheet-engaging heads and with studs detachably engaging said binding bars, said posts being arranged in coacting pairs in overlapping relation and being of semi-cylindrical complementary cross section, their ends being outwardly beveled, and coupling members for said binding bars disposed at the ends thereof.

4. In a temporary binder, the combination of covers, binding bars operatively associated therewith, sheet-engaging posts provided with sheet-engaging heads and with studs detachably engaging said binding bars, said posts being arranged in coacting pairs in overlapping relation, and coupling members for said binding bars disposed at the ends thereof.

5. In a temporary binder, the combination of covers, binding bars operatively associated therewith, sheet-engaging posts provided with sheet-engaging heads and detachably engaging said binding bars, said posts being arranged in coacting pairs in overlapping relation and being of complementary cross section, and means for adjustably connecting said binding bars.

6. In a temporary binder, the combination of covers, binding bars operatively associated therewith, sheet-engaging posts provided with sheet-engaging heads and detachably engaging said binding bars, said posts being arranged in coacting pairs in overlapping relation so that the posts of each pair are adapted to enter the same sheet opening, and means for adjustably connecting said binding bars. 40

7. In a temporary binder, the combination of covers, binding bars operatively associated therewith, sheet-engaging posts provided with sheet-engaging heads and detachably engaging said binding bars, said posts being arranged in coacting pairs in overlapping relation and being of complementary cross section, and means for connecting said binding bars. 50

8. In a temporary binder, the combination of covers, binding bars operatively associated therewith, sheet-engaging posts provided with sheet-engaging heads and detachably engaging said binding bars, said posts being arranged in coacting pairs side by side in overlapping relation so that the posts of each pair are adapted to enter the same sheet opening, and means for connecting said binding bars. 60

In witness whereof, I have hereunto set my hand and seal in the presence of two witnesses.

GEORGE P. WIGGINTON. [L. S.]
